UNITED STATES PATENT OFFICE.

LYLE WARREN GEER, OF HOLSTEIN, IOWA, ASSIGNOR OF ONE-FOURTH TO PETER J. A. SCHNOOR, OF HOLSTEIN, IOWA.

WASHBOARD.

1,060,564.

Specification of Letters Patent. Patented Apr. 29, 1913.

Application filed May 16, 1912. Serial No. 697,764.

To all whom it may concern:

Be it known that I, LYLE WARREN GEER, a citizen of the United States, residing at Holstein, in the county of Ida and State of 5 Iowa, have invented certain new and useful Improvements in Washboards, of which the following is a specification, reference being had to the accompanying drawings.

This invention comprehends certain new 10 and useful improvements in washboards and has for its object to provide a washboard which will catch and retain a major portion of the dirt washed from the clothes.

Another object of the invention is to provide 15 a washboard which may be easily cleaned.

The invention also aims to generally improve devices of this nature to render them more useful and commercially desirable.

20 With these and other objects as shall become apparent as the description proceeds, the invention consists in certain novel constructions, and arrangement of parts as I shall hereinafter fully describe and claim.

25 For a complete understanding of the invention reference is to be had to the following description and accompanying drawing, in which—

Figure 1 is a front view of a washboard 30 constructed in accordance with my invention; Fig. 2 is a vertical sectional view showing the scrub-screen swung at an angle to the pan; Fig. 3 is a transverse section on line 3—3 of Fig. 1; and Fig. 4 is a transverse 35 section on the line 4—4 of Fig. 1.

Similar parts are referred to in the description and designated in the accompanying drawing by like reference characters.

Referring to the drawing by numerals, 1 40 designates a rectangular metallic pan having the bottom 2, the side walls 3 and the end walls 4 and 5. The side walls 3 are extended beyond the end wall 5 to form the legs 6 having hinged to their extremities the outwardly 45 extending stops 7 which engage the walls of a tub and maintain the washboard at the proper angle for work. A partition 8 extending across the upper portion of the pan 1 divides it into two compartments, the 50 smaller one designated 9 forming the soapbox.

A scrub screen 10 having its edges secured in the frame 11 is pivotally secured at its upper end between the side walls 3 adjacent 55 the partition 8 by the screw fastenings 12.

To brace the scrub-screen and space it from the bottom 2 of the pan 1 I provide the flanges 13 on the inner side of the walls 3 parallel to and below the outer edge thereof, and the parallel ribs 14 running longitudinally of the pan 1. These ribs and flanges extend from the partition 8 to the catch basin 15 and have their top edges upon which the scrub screen 10 rests, below the top of the pan 1. 60

I form the catch-basin 15 at the lower end of the pan 1 by providing an inwardly extending transverse flange 16. This flange is formed on the wall 5 adjacent its outer edge and extends entirely across the pan 1 70 parallel to the bottom 2 and on a level with the top of the ribs 14 and flanges 13.

When in use the washboard stands in a tub and the clothes are rubbed on the scrub-screen 10. The water and dirt coming from the soiled clothes runs through the screen into the pan 1 and is collected in the catch basin 15. The major portion of the dirt remains in this basin while the water runs through the aligned openings 17 back into the 80 tub. It will be apparent that this provision for catching the dirt washed from the soiled clothes is of great advantage in so much as it prevents the wash water becoming as dirty as would otherwise be the case. When it 85 is desired to clean the pan 1 and remove the dirt from the catch basin 15, the scrub screen 10 is swung outwardly about the pivots 12 giving free access to the portions beneath. 90

From the foregoing description in connection with the accompanying drawing it will be seen that I have provided a simple and durable washboard which may be constructed entirely of metal and designed so as to 95 collect and retain a large amount of the dirt washed from soiled clothes.

It is to be understood that minor changes in shape and construction may be made without departing from the spirit and scope 100 of the invention as defined by the claims.

What I claim is:—

1. A washboard comprising a shallow pan having a body wall, and side flanges formed integrally therewith and extended longitudinally beyond one end of the same to form legs, one end of the body wall being bent upon itself in U shaped form to provide a catch basin and a scrub screen pivotally secured at one end and adapted to swing into 110

parallel spaced relationship with the body wall of said pan.

2. A washboard comprising a shallow rectangular pan having an imperforate body wall, side walls formed integrally therewith and extended beyond one end of the same to form legs, and end walls, an inwardly projecting transverse flange formed on the end wall which is adjacent said legs, 10 the flange coöperating with said end wall and the body wall to form a catch basin **U** shaped in cross section, a scrub screen

hingedly secured at one end between the side walls of said pan, said scrub screen being adapted to swing into parallel spaced relationship to the body wall of the pan and be held in said spaced relationship by engagement with the catch basin. 15

In testimony whereof I hereunto affix my signature in the presence of two witnesses. 20

LYLE WARREN GEER.
